United States Patent Office

Des. 220,656
Patented May 4, 1971

220,656

METALLURGICAL OPAQUE PROJECTOR

Paul Rosenthal, 83-09 Talbot St.,
Kew Gardens, N.Y. 11415

Filed Oct. 13, 1969, Ser. No. 19,530

Term of patent 14 years

Int. Cl. D16—03, 04

U.S. Cl. D61—1

FIG.1

FIG.2

FIG.4

FIG.3

FIG.5

FIG. 1 is a top plan view of the metallurgical opaque projector showing my new design;

FIG. 2 is a side elevation thereof;

FIG. 3 is a front elevation thereof;

FIG. 4 is a rear elevation thereof; and

FIG. 5 is a bottom plan view of the metallurgical opaque projector taken on a smaller scale.

I claim:

The ornamental design for a metallurgical opaque projector, as shown.
